UNITED STATES PATENT OFFICE.

LE ROY WILSON KELSBY, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC HAND TELEPHONE.

Application filed September 24, 1920. Serial No. 412,594.

To all whom it may concern:

Be it known that I, LE ROY WILSON KELSBY, a citizen of the United States, residing at New York, in the county of New York, 5 State of New York, have invented certain new and useful Improvements in Automatic Hand Telephones, of which the following is a full, clear, concise, and exact description.

10 This invention relates to hand telephones provided with impulse transmitters and adapted for use with automatic telephone systems. These hand telephones are particularly, although not exclusively, used by 15 telephone repair-men.

The general object of the invention is to provide a new and improved automatic hand telephone which has the advantages, among others, of compactness, good balancing, and protection of the impulse transmitter from harm.

The invention is characterized in general by the location of the impulse sender on the handle of the instrument intermediate 25 the receiver and the transmitter; and specifically by the location of the impulse sender in a cavity in the handle and on the same side of the latter on which the receiver and transmitter are mounted.

30 The invention will be understood from the following detailed description taken in connection with the accompanying drawing, in which Figs. 1 and 2 show in perspective two embodiments of the invention.

35 Referring to both Figs. 1 and 2, the handle portion of the hand telephone is shown at 3 and 3', the receiver portion at 4 and 4', and the transmitter portion at 5 and 5'. These may be any suitable form.

40 In the embodiment shown in Fig. 1, the impulse transmitter 6, which is preferably of the dial type, is mounted on the handle 3, on the same side thereof as the receiver and transmitter, and intermediate 45 the latter. In the embodiment shown in Fig. 2, the impulse transmitter 6' is mounted on the handle 3', on the side opposite to that on which the receiver 4' and the transmitter 5' are located. In both embodiments of

50 the invention, the handle portion of the instrument is provided with a cavity within which the impulse transmitter is mounted and is thereby protected from injury.

Hand telephones of this kind are usually provided with two button-operated switches, 55 one of which, when its button is depressed, short circuits a condenser located in the receiver and transmitter circuit; and the other, when depressed, opens a short circuit around a resistance located in the line circuit. One 60 of these buttons is shown at 7 and 7' in Figs. 1 and 2. The other button, not shown, is similar to button 7 (or 7') and symmetrically disposed with respect to it on opposite side of the handle. One of these buttons 65 may, therefore, be conveniently operated by the thumb and the other by the forefinger. The openings 8 and 8' in the end of each hand telephone allow the line conductors to be led in to terminals on the inside of 70 the instrument.

It is of course understood that the hand telephones herein shown and described may be modified as regards their design and form without departing from the spirit of the 75 invention as defined in the claims.

What is claimed is:

1. In an automatic hand telephone, the combination of a handle, a telephone receiver and a telephone transmitter secured 80 to opposite ends thereof, and an impulse transmitter mounted on the handle intermediate the receiver and transmitter.

2. In an automatic hand telephone, the combination of a telephone receiver, a telephone transmitter, a handle portion to the opposite ends of which the receiver and the transmitter are secured, said handle portion having a cavity, and an impulse transmitter mounted in said cavity. 85

3. In an automatic hand telephone, the combination of a telephone receiver, a telephone transmitter, a handle portion to the opposite ends and on the same side of which the receiver and the transmitter are 95 mounted; and an impulse transmitter mounted on the handle on the same side thereof as the receiver and transmitter and intermediate the latter.

In witness whereof, I hereunto subscribe 100 my name this 21st day of September, A. D. 1920.

LE ROY WILSON KELSBY.
